CLAIM

The ornamental design for a receiver for shot gun, as shown and described.

DESCRIPTION

FIG. 1 is an elevational view of a receiver for shot gun, showing my new design;

FIG. 2 is a top plan view thereof;

FIG. 3 is a right side elevational view thereof;

FIG. 4 is a left side elevational view thereof; and,

FIG. 5 is a rear elevational view thereof.

The broken line showing of the remainder of a shotgun handle is for illustrative purposes only and forms no part of the claimed design.
